UNITED STATES PATENT OFFICE.

JOHN F. O'CONNOR, OF CHICAGO, ILLINOIS, ASSIGNOR TO WILLIAM H. MINER, OF CHAZY, NEW YORK.

RAILWAY-CAR DRAFT-RIGGING.

1,258,935.

Specification of Letters Patent. Patented Mar. 12, 1918.

Application filed March 3, 1915. Serial No. 11,717.

To all whom it may concern:

Be it known that I, JOHN F. O'CONNOR, a citizen of the United States, residing at Chicago, in the county of Cook and State of Illinois, have invented a certain new and useful Improvement in Railway-Car Draft-Riggings, of which the following is a full, clear, concise, and exact description, reference being had to the accompanying drawings, forming a part of this specification.

This invention relates to improvements in railway car draft riggings.

Objects of the invention are to provide a draft rigging for railway cars which comprises few parts, compactly arranged and readily assembled and disassembled.

Other objects of the invention are the provision of: A rigging for railway cars wherein in a yoke is detachably connected to the draw-bar; a yoke comprising two members and together having a friction shell formed integrally therewith; integral means on the two pieces of the yoke and elements of the friction mechanism which coöperate to prevent lateral separation of the yoke members; and a single fixed key by which all the buff and draft shocks are transmitted to the sills, said key preventing rearward movement of the yoke under buff and preventing forward movement of certain elements of the friction mechanism under draft.

The invention furthermore consists in the improvements in the parts and devices and in the novel combinations of the parts and devices, as herein shown, described and claimed.

In the drawing forming a part of this specification, Figure 1 is a central, longitudinal vertical section view of a draft rigging embodying my improvements, the coupler being shown in side elevation. Fig. 2 is a horizontal combined sectional and plan view, the parts in section being taken substantially on the line 2-2 of Fig. 1. Fig. 3 is a transverse vertical sectional view taken on the line 3-3 of Fig. 1. Fig. 4 is a view similar to Fig. 3 illustrating another embodiment of my invention. Fig. 5 is a side elevation of another form of yoke embodying my invention and Fig. 6 is a detail perspective showing another form of friction shoe suitable for use with my improvements.

In said drawing, and referring to Figs. 1 to 3 inclusive, 10-10 denote the center sills 55 to the inner sides of which are attached re-

inforcing plates 11-11, said plates and sills being slotted to removably receive there-through a relatively fixed transverse key 12, the key being held in place by any suitable means such as cotters 13. The draw-bar 14 is shown as of the M. C. B. type and provided with upper and lower shoulders 15 with which coöperate under draft, inturned shoulders 16 formed at the front ends of two loop-like members 17-17 which together form a yoke designated generally by the reference A. Each of said yoke members 17-17 is preferably of like construction and comprises an upper arm 18, lower arm 19 and side wall 20 which extends from the front to a point somewhat to the rear of the longitudinal center thereof. The upper and lower arms 18-19 of each yoke member are provided on their inner faces, as clearly indicated in Figs. 1 and 3, with friction surfaces 21-21, each of said surfaces as shown in the structure illustrated in Figs. 1 to 3, being longitudinally grooved as indicated at 22. Reinforcing ribs 23 are provided on the outer surfaces of the yoke members surrounding the friction shell formed integrally therewith. The yoke members at their rear ends, are open at the sides as clearly indicated in Fig. 1 to thereby permit the insertion of the spring 24, spring follower 25, friction shoes 26 and follower wedge block 27. The sides 20 of the yoke members are also provided with elongated slots 28 through which the key 12 extends, said slots being so arranged that the yoke is permitted forward movement relatively to the key but is prevented from rearward movement. Said slots 28 are surrounded by laterally extending flanges 29 arranged to strengthen the yoke and also to assist in centering the yoke between the center sills.

As clearly shown in Fig. 1, the follower wedge block 27 has an elongated centrally located slot 30 through which the key 12 extends, said slot 30 being open at its front end and so arranged as to permit the inward movement of the wedge but preventing its outward movement. The friction shoe 26 and wedge block 27 are provided with inclined faces in the usual manner and having anti-friction rollers 31 therebetween. As most clearly shown in Fig. 3, each of the friction shoes 26 is provided with a pair of integral longitudinally extending ribs 32 arranged to slide and engage in the longi-

tudinally extending grooves 22 formed on the inner faces of the friction shell portions of the yoke. As will be apparent, the friction shoes with these ribs cooperate with the grooves to prevent lateral separation of the two yoke members when the parts are in assembled position.

The operation is as follows: Upon outward movement of the draw-bar, that is, under draft, the yoke A is pulled forwardly due to the engagement of the shoulders 15 and 16. During this movement, the wedge 27 is held stationary and pressure from the friction shoes to the friction shell formed on the interior of the yoke is increased as the spring 24 is gradually compressed. Under buff, the yoke A is prevented from rearward movement, thus causing the rear connecting portion of the yoke to serve as a rear stop for the spring 24. The draw-bar is free to move inwardly relatively to the yoke under buff, thereby forcing the wedge block 27 inwardly and exerting pressure from the wedge through the shoes to the friction shell, which is resisted by the spring 24 in the usual manner.

In Fig. 4, the contour of the yoke at the section where the friction shell is provided is somewhat changed, as is also the shape of the friction shoes. As shown, the yoke members 117-117 have their upper and lower arms 118 and 119 inclined inwardly toward the center of the gear proper. The corresponding friction surfaces 121-121 are similarly inclined and coöperable therewith are correspondingly inclined friction surfaces 132 on the friction shoes 126. On account of the arrangement of the inclined friction surfaces of the shell and shoes, it is apparent that spreading or separation of the yoke members is prevented when the parts are in assembled position.

In Fig. 5, a somewhat different form of means for attaching the yoke to the draw-bar is provided. In this instance, the yoke A' has the side walls 220 thereof provided with forward extensions 240, the same being provided with elongated coupler key slots 241 by which the yoke may be keyed to the draw-bar when the latter has a coupler key slot. The key slot 241 is made longer than the coupler key so as to permit the draw-bar to move inwardly relatively to the yoke under buff, the yoke being held stationary in the same manner as described for the construction shown in Figs. 1 to 3.

In Fig. 6, a different form of friction shoe 326 is shown, the same having a plurality of longitudinally arranged, cylindrically hardened inserts 332 on its outer face. As clearly shown, each of these inserts 332 has a portion thereof projecting beyond the normal surface of the friction shoe and these projecting portions of the inserts are adapted to slide in and coöperate with cor-

respondingly curved grooves in the surfaces of the friction shell (not shown) of a yoke.

Although I have herein shown and described what I now consider the best means of carrying out my invention, yet it will be understood by those skilled in the art that numerous changes and modifications may be made in the details of construction and arrangement of parts, without departing from the spirit of the invention, and all such changes and modifications are contemplated as come within the scope of the claims appended hereto.

I claim:

1. In a draft rigging, the combination with a draw bar and a yoke, the draw bar being movable inwardly independently of the yoke under buff, of a friction shell carried by and rigid with respect to said yoke, friction shoes coöperable with said shell, said shoes being arranged one above the other, a wedge coöperable with said shoes, a spring, and means preventing outward movement of said wedge and permitting inward movement thereof. 90

2. In a draft rigging, the combination with draft sills, of a member stationary with respect to said sills, a yoke slidably forwardly relatively to said member and prevented from rearward movement thereby, said member extending through the yoke, a draw bar arranged to pull said yoke forwardly, the draw bar being movable inwardly independently of the yoke, a friction shell formed integrally with said yoke, 95 and a single set of friction devices coöperable with said shell under both buff and draft. 100

3. In a draft rigging, the combination with the sills, of a draw-bar, a yoke, said yoke and draw-bar having coöperating integral interengaging means arranged to be disconnected without destructive effect and arranged to pull the yoke forwardly under draft, means preventing rearward movement of the yoke upon rearward movement of the draw-bar, and a friction shell formed integrally on the interior of said yoke. 105

4. In a draft rigging, the combination with a draw-bar, of a yoke detachably connected with said draw-bar, a friction shell rigid with said yoke, a single set of friction devices coöperable with said shell, under both buff and draft, a spring, and fixed means preventing rearward movement of said yoke and also preventing forward movement of one of the friction devices. 115

5. In a draft rigging, the combination with a two piece yoke having a friction shell formed on the interior thereof, of friction devices coöperable with said shell and including friction shoes, and coöperating means on the shoes and shell preventing separation of said yoke pieces when the parts are in assembled position. 125

6. In a draft rigging, the combination with a yoke consisting of two parts arranged side by side, of means for preventing separation of said members, said means comprising elements slideable with respect to and within said members.

7. A yoke for draft riggings having parallel, spaced arms and provided with an opening in the sides thereof, the inner faces 10 of said arms being constructed in the form of a friction shell with the friction surfaces arranged parallel with said arms and disposed opposite each other, said arms adjacent the friction surfaces being united by 15 integral side walls.

8. In a draft rigging, the combination with a draw-bar, of a yoke movable with said draw-bar under draft, a key extending transversely through said yoke and arranged 20 to hold the latter stationary under buff, a friction shell formed integrally on the interior of said yoke, said key passing between the friction surfaces of said shell, friction devices coöperable with said shell, 25 and a spring, said key preventing outward movement of one of said friction devices under draft.

9. In a draft rigging for railway cars, the combination with a draw-bar and yoke 30 having inter-engaging shoulders, said yoke having an integral friction shell formed on the interior thereof, friction shoes coöperable with said shell, a wedge coöperable with said shoes, a spring, and a stationary 35 key extending transversely through said wedge, said key preventing forward movement of the wedge and preventing rearward movement of the yoke.

10. In a draft rigging, the combination 40 with a draw-bar, of a yoke having an integral friction shell formed on the interior thereof, means for pulling said yoke forwardly upon forward movement of the draw-bar, friction shoes mounted within

said yoke, a wedge coöperable with said 45 shoes, a spring, and a stationary transversely extending key engaging said wedge and said yoke and preventing forward movement of the former and rearward movement of the latter.

11. In a draft rigging, the combination with a yoke formed by two members arranged side by side, of friction mechanism associated with said yoke, parts of said friction mechanism being provided with means 55 to prevent lateral separation of said two yoke members.

12. In a draft rigging, the combination with a draw bar, of a yoke, the yoke having an integral friction shell intermediate its 60 ends, said shell having upper and lower friction surfaces and side walls connecting said upper and lower surfaces, friction shoes mounted within said shell, a spring against which said shoes act, a wedge coöperating with said shoes, and means for holding said wedge stationary during movement of the yoke in one direction.

13. As an article of manufacture, a friction yoke for railway draft riggings, said 70 friction yoke comprising two separable loop-shaped members having parallel arms, said arms being provided with opposed friction faces for a portion of their lengths intermediate their ends, each of said pair of 75 arms being connected by an integral web extending between those portions of the yoke arms having the friction faces formed thereon, the yoke being open to the rear of said connecting portions whereby, when the 80 yoke members are assembled, an inclosed friction shell is formed intermediate the ends of the yoke and the yoke at the rear of said friction shell is open to receive a spring.

JOHN F. O'CONNOR.
